Atty.

UNITED STATES PATENT OFFICE.

JAMES A. HINSON, OF DES MOINES, IOWA, ASSIGNOR TO THE HINSON CAR COUPLER COMPANY, OF SAME PLACE.

CAR-COUPLING.

SPECIFICATION forming part of Letters Patent No. 398,324, dated February 19, 1889.

Application filed September 26, 1888. Serial No. 286,431. (No model.)

To all whom it may concern:

Be it known that I, JAMES A. HINSON, a citizen of the United States, residing at Des Moines, in the county of Polk and State of Iowa, have invented certain new and useful Improvements in Car-Couplers; and I do hereby declare the following to be a full, clear, and exact description of the invention, such as will enable others skilled in the art to which it appertains to make and use the same.

This invention relates to car-couplers, and more particularly to that class known as "twin jaws," in which a pivoted or swinging jaw automatically interlocks with a similar jaw to effect the coupling; and it has for its object to provide a very simple device for limiting the movement of the swinging jaws in order that they may always be held in the exact position to readily effect the coupling and are prevented swinging outward beyond the desired distance; and it consists of the parts and combinations of parts hereinafter described and claimed.

In the accompanying drawings, forming a part of this specification, Figure 1 is a perspective view of my improved coupler; Fig. 2, a section on the line *x* *x*, Fig. 1; Fig. 3, a perspective view of the jaw; Fig. 4, a view of the latch, and Fig. 5 a plan view of the latch and movable jaw.

Similar letters refer to similar parts throughout the several views.

A represents the draw-bar, which is cast hollow, as is usual, and adapted to be secured to a car in such manner as to permit a limited longitudinal movement in coupling the cars, and abuts against a spring to deaden the force of the concussion. At its outer or enlarged end the draw-bar is formed with curved and flaring arms *B* *B'*, the latter being merely a guard or guide arm to insure the entrance of the swinging or movable jaw on the opposite coupler between the guard-arm and movable jaw *D* to effect the coupling. A hollow offset or hood-shaped projection, *E*, is cast integral with the draw-bar at its enlarged head, forming a shoulder adapted to abut against the front beam of the car when the draw-bar is driven back. The arm *B* of the draw-bar is cast with flanges *C*, having circular recesses *a* formed in their contiguous faces and slots

b entering said recesses from the outer edges of the flanges, for a purpose which will be described hereinafter.

Between the arms *B* *B'* the head is hollowed out in order to receive the hook-shaped projection *g* on the branch *h* of the movable jaw *D* when the coupling is made. As clearly shown in Fig. 3, the movable jaw is formed with the branches *h* *h'*, the former, when the jaw is in position on the draw-bar, extending back into the hollowed-out portion of the head, and having its outer surface and end tapered off, so that it will the more readily slip past the latch *H* in coupling the cars. The branch *h'* is rounded off or curves on its outer face, as shown in Fig. 3 at *m*, to form a buffer, and has a slot or pocket, *n*, formed through the same at about its center to receive a link when it is desired to couple together cars, one of which is provided with the link-and-pin coupling only. A perforation or opening, *o*, is formed through the body of the branch *h'*, at right angles to the slot *n*, to receive a pin to secure the link in place and complete the coupling. On the body of the jaw *D*, back of the junction of the branches *h* *h'*, oblong journals *p* are cast, the jaw being cut away or reduced at this point, so that a flat surface is left about the journals, such reduction leaving shoulders *r* at the ends of the branch *h'*, which is curved or hollowed out so as to fit the rounded ends of the flanges *C* of arm *B* snugly. The journals are cast at right angles to the curved shoulders. The journals in length are adapted to fit the recesses *a*, formed in the flanges *C*, and are inserted endwise through the slots *b*, which are only sufficiently wide to admit them into said recesses, and the jaw is given a short turn, so as to bring the journals lengthwise across the inner ends of said slots, and thus prevent their accidental displacement.

On the outer side of the branch *h* at its upper surface is cast a shoulder or projection, *d*, which extends from said branch at an acute angle, the outer face or end of said projection being tapered and its face *d'* being flat, as shown in Fig. 3. This projection fits into a recess, *c*, formed in the enlarged head immediately in the rear of arm *h'*. The latch *H*, as clearly shown in Fig. 4, is provided with a

projection or shoulder, *s*, which extends therefrom at an acute angle, and at its upper end a concave recess, *t*, is formed in the latch immediately above a shoulder, *u*. The body of the latch is formed with an enlargement, *v*, at its center, and perforations are formed in each end of said latch. The latch is inserted into the head of the draw-bar through a slot, *f*, formed in the same in its lower portion beneath the hood *E*, and is pivotally secured in said hood by a pin, *e*, which passes through the perforations in the walls of the hood and the upper end of the latch. The slot *f* is of sufficient length to permit the back-and-forth play of the latch, the end of the latter projecting through said slot a short distance, and being connected with a rod, *K*, suitably mounted on the frame of the car by means of a chain, *L*. The latch is held forward or against the front end of the slot *f* by a spiral spring, *M*, (see Fig. 2,) which fits partly in the concave recess *t*, and rests on the shoulder *u* at one end and against the upper wall of the hood at the other. When the latch is in position, the side of its projection *s* fits against the enlarged head at *w*, and its upper surface against the part *w'*, while the projection *d* of the arm *h* prevents the movable jaw from being thrown outward too far by coming in contact with said projection *u* on latch *H*, as shown in Fig. 5, in which the jaw is shown open to its full limit and in position to be coupled.

In order to couple cars provided with my improved coupler, the movable jaws are set as shown in Figs. 2 and 5—that is, with the branch *h* outside of the latch *F*. The cars are then brought together, the branches *h'* of the couplers on each car entering the space between arms *B'* and the respective branches *h'* and pushing branch *h* back against the latch, whose spring permits it to recede until the hook-shaped end *g* of branch *h* passes it,

when the spring throws the latch forward, and thus locks the branch *h* in place. In order to uncouple the cars, the rod *K* is turned from the side of the car, so as to wind the chain *L* around it, and thus draw the latch back, when the movable jaw may be easily thrown out into the position shown in Fig. 5, ready to be coupled. 45 50

Having thus described my invention, what I claim as new, and desire to secure by Letters Patent, is—

1. The combination, in a car-coupler, of the draw-bar, the hollow hood cast therewith, the enlarged head having the recess *c* therein, the latch pivotally suspended in said hood and having the projection *s*, the spring adapted to move said latch forward, the movable jaw having the branches *h* *h'* journaled to said enlarged head, and said branch *h* having the projection *d* cast integral therewith, substantially as described. 55 60

2. The combination, in a car-coupler, of the draw-bar having an enlarged head provided with the recess *c*, the arms *B* *B'*, cast integral with said head, the latch pivotally suspended with said head and having the projection *s*, the movable jaw having the branches *h* *h'* 70 journaled to one of said arms, and a spring for moving the latch forward, substantially as described. 65

3. The combination, in an automatic car-coupler, of the pivoted latch having the projection extending therefrom at an acute angle, and the movable jaw having branches *h* *h'*, the former having a projection, *d*, cast integral therewith, substantially as described. 75 80

In testimony whereof I affix my signature in presence of two witnesses.

JAMES A. HINSON.
